Filed Oct. 7, 1963, Ser. No. 76,887

Term of patent 14 years

(Cl. D55—1)

FIG. 1 is a side elevation view of an in-line slip clutch showing our new design;

FIG. 2 is an end elevation view taken along line 2—2 of FIG. 1;

FIG. 3 is another side elevation view similar to FIG. 1 but rotated 90° about the longitudinal axis thereof;

FIG. 4 is an end elevation view taken along line 4—4 of FIG. 3;

FIG. 5 is a side elevation view of another embodiment of my design;

FIG. 6 is an end elevation view thereof taken from the right of FIG. 5;

FIG. 7 is a side elevation view of another embodiment of my design;

FIG. 8 is a side elevation view thereof taken from the left of FIG. 7.

The sides opposite those shown in FIGS. 1, 3, 5 and 7 are mirror images of the respective views. The body portions of the embodiments shown in FIGS. 5 and 7 are substantially identical to the corresponding body portion shown in FIGS. 1 through 4.

We claim:

The ornamental design for an in-line slip clutch, substantially as shown and described.
